CLAIM

The ornamental design for a anti pinching contact, as shown and described.

DESCRIPTION

FIG. 1 is a top front left perspective view of an anti pinching contact showing my new design;

FIG. 2 is a front plan view thereof.

FIG. 3 is a rear plan view thereof.

FIG. 4 is a left plan view thereof.

FIG. 5 is a right plan view thereof.

FIG. 6 is a top plan view thereof; and,

FIG. 7 is a bottom plan view thereof.

The dot-dash broken lines depict the bounds of the claimed design, while all evenly spaced broken lines are directed to environment. The broken lines form no part of the claimed design.

1 Claim, 6 Drawing Sheets
